UNITED STATES PATENT OFFICE.

GEORGE F. SARGENT, OF NEW YORK, N. Y.

INVALID-BEDSTEAD.

SPECIFICATION forming part of Letters Patent No. 274,392, dated March 20, 1883.

Application filed July 24, 1882. (No model.)

To all whom it may concern:

Be it known that I, GEORGE F. SARGENT, of New York city, in the county of New York and State of New York, have invented certain new and useful Improvements in Invalid-Bedsteads; and I do hereby declare that the following is a full, clear, and exact description thereof.

This invention relates to certain improvements on that for which Letters Patent were granted to William S. Groff under date of July 29, 1879, No. 218,016; and it consists in certain novel details of construction, arrangement, and combination, as hereinafter more particularly described, and pointed out in the claims.

In the accompanying drawings, Figure 1 is a perspective view of a bedstead embodying my improvements. Fig. 2 is a longitudinal vertical sectional view of the same. Fig. 3 is a transverse vertical sectional view. Figs. 4 and 5 are detail views of certain detached parts.

The bedstead is constructed with side rails, A, head and foot rails A², and posts A³, which may be of any suitable construction. The posts A³ are attached to the head and foot rails A² in a permanent manner, and the side rails, A, are connected to said posts by fastenings of the usual or any suitable construction.

The mattress is attached to and carried by the side rails, A. It is made in four sections, B B² B³ B⁴. The section B² is rigidly attached to the side rails, A. The section B is hinged to the section B², so that it can be raised and lowered in order to change the occupant from a recumbent to an upright position, and vice versa. The section B³ is hinged to the rigid section B², and the section B⁴ is hinged to the section B³. The section B supports the portion of the body of the occupant above the hip-joints, the section B³ the portion between the hip-joints and knee-joints, and the section B⁴ the portion below the knee-joints. The sections B and B³ may be provided with removable portions, and the section B⁴ may be divided longitudinally, as shown and described in the patent before referred to. The section B is provided with a pillow or head rest, B⁵, which has its lower edge hinged to the other portion, so that it may be inclined at

an angle with relation thereto. At each end of this pillow or head-rest is a curved slotted bar, b, extending downward from its under side, and engaging with a thumb-screw, b², in the side piece of the section, by which means the pillow or head-piece is held in position at different angles.

In the patent of Groff, before referred to, the head-section is held in different positions by means of notched bars engaging with pins or projections. In my invention the head-section B is raised and lowered and held in position by means of devices constructed and operating as follows: In the side rails, A, is journaled a shaft, C, which is provided with a right-hand and a left-hand screw-thread, extending from the middle of said shaft toward the ends. On these threads are two nuts, c c, each of which is formed with a perforated lug, to which is pivoted the lower end of a rod, D. The rods D D cross each other like the letter X, and the upper end of each rod is pivoted to a coupling, E, of the form shown in detail in Figs. 4 and 5. This coupling is formed with two pivots, e e, extending in opposite directions, and two perforated lugs, e² e², at right angles to said pivots. The coupling is dropped through a slot in the bottom board of the head-section, provided with bearings for the pivots e, and the end of the rod D is pivoted between the lugs e² by means of a bolt or rivet, f, as shown in Fig. 4. By this construction a universal joint is formed. When the shaft C is turned in one direction the nuts c c travel toward the middle of the shaft, carrying with them the lower ends of the rods D D, and thus causing the upper ends of said rods to elevate the section B. When the shaft C is turned in the opposite direction the nuts c c travel toward the ends of the shaft, thus causing the upper ends of the rods D D to descend and lower the section B. By this means the section is raised and lowered by a steady and uniform motion, without any jar or shock to the occupant of the bed. The shaft may be turned by a crank, knob, key, or any other suitable means. These devices may be applied to a lounge or couch, in which case the shaft may be attached to the section and the couplings to the rails A.

In the patent of Groff, before referred to, no provision is made for raising the section

which supports the portion of the body between the hip-joints and knee-joints. In this invention the section B³ is raised and lowered by means of a screw-shaft, G, and rods H H, arranged and operating in a similar manner to those just above described. By this means the knees of the patient may be raised above the level of the hip-joints either in connection with the raising of the section B or independently thereof, as may be desired. The section B⁴ is provided with a removable foot-rest consisting of a cushion, J, having pins i, for engagement with sockets in the frame of the section. The sections B B³ are provided with removable and adjustable arms, similar to the arms of a chair. These arms K are provided with pins k², for engagement with sockets in the frame of the section B, and pins k³, for engagement with sockets in the frame of the section B³. Said pins are connected to the arms by pivots or hinge-joints, so as to allow the arms to adjust themselves to the different positions of the sections.

The upper ends of the posts A³ are connected by rods a, the ends of which pass into slots or mortises in the posts, and are secured by wedges a². On the tops of the side rods, a, rests a bar, a³, running transversely of the bed. On the top of this bar a³, and on the rod which connects the two foot-posts, rest two bars, L L, the ends of which are transversely grooved to fit said bar and rod, and are provided with thumb-screws l, for holding them firmly in position. Each of the bars L is slotted for nearly its entire length, and in each slot work three screw-eyes, M, provided with thumb-nuts m, for holding them in place in different positions. To each of the screw-eyes is attached the upper end of a cord, m², the lower end of which is attached to a cradle for holding the leg of the occupant of the bed. This cradle is made in two parts, N N², hinged together at their contiguous ends to correspond with the knee-joint of the patient, so that the leg may be held either straight or bent at any desired angle. By means of the two bars L L provision is made for expanding or contracting the curvature of the cradle, and thereby regulating the pressure upon the leg to suit the convenience of the patient by moving said bars farther from or nearer to each other.

To the two foot-posts of the bedstead is attached a bar, P, the ends of which are forked, so as to grasp the posts. In each fork are sawed two kerfs, p p, so as to give a certain degree of elasticity to the branches of the fork. Through the portion of the fork in which the kerfs are located passes a thumb-screw, S, provided with a right-hand thread for engagement with one branch and a left-hand thread for engage-

ment with the other branch of the fork, so that by turning the thumb-screw in one direction the branches of the fork are drawn toward each other and made to clamp the post, and by turning it in the other direction the fork is loosened, so that the bar may be raised or lowered. By this means provision is made for adjusting the bar to any desired height on the posts.

On the under side of the bar P are pulleys R, over which pass cords r, attached to the leg-sections B⁴, by which means provision is made for raising and holding the leg-sections above the level of the hip-section B³ when desired.

In the inner sides of the side rails, A, near the foot of the bedstead, are grooves T, in the lower edges of which are notches t. A rod, V, is arranged with its ends resting in these grooves and notches, so as to support the leg-sections B⁴. By changing the position of the rod to the different notches the sections are firmly supported in different positions.

On the top of the bar P is journaled a roller, W, which is secured to the lower end of the cradle-section N², and over which passes a cord, w, provided with a weight, w². By this means provision is made for balancing the leg and foot of the patient at any desired position above the level of the body.

Having thus described my invention, what I claim as new, and desire to secure by Letters Patent, is—

1. The hinged section B⁴, provided with rods V, in combination with the posts A³ and rails A, provided with notched grooves T, substantially as shown and described.

2. The side rails and stationary section B², secured thereto, in combination with the hinged sections B B³ and actuating mechanism, and the arms K, provided with hinged supports k² k³, movably secured to the adjustable sections, as described.

3. In combination with the hinged two-part cradle N N², the laterally-adjustable slotted bars L, provided with set-screws l and the supporting-bars a' a³, and the cords m², substantially as shown and described.

4. The combination of the adjustable bar P, the roller W, and weighted cord w, the posts A³, and cradle-section N², substantially as shown and described.

5. The combination of the adjustable bar P, the roller R, and weighted cord r, the posts A³, and hinged section B⁴, substantially as shown and described.

GEO. F. SARGENT.
